UNITED STATES PATENT OFFICE.

CYRIL FARNY, OF DE KALB, ILLINOIS, ASSIGNOR TO WURLITZER GRAND PIANO COMPANY, OF DE KALB, ILLINOIS, A CORPORATION OF ILLINOIS.

DESIGN FOR A GRAND-PIANO CASE.

Application filed March 7, 1927. Serial No. 20,996. Term of patent 14 years.

To all whom it may concern:

Be it known that I, CYRIL FARNY, a citizen of the United States, residing at De Kalb, in the county of De Kalb, in the State of Illinois, have invented a new, original, and ornamental Design for Grand-Piano Case, of which the following is a specification, reference being had to the accompanying drawings, forming a part thereof.

In the drawings:—

grand piano case embodying my new design as it appears with the cover closed and as viewed mainly from the front.

Figure 2 is a perspective of the piano as seen from the side and with the cover in raised position.

I claim:

The ornamental design for a grand piano case substantially as shown.

CYRIL FARNY.
